UNITED STATES PATENT OFFICE

SPENCER U. BOEHMER, OF LOMBARD, ILLINOIS

DESIGN FOR A BOTTLE

Application filed October 10, 1929. Serial No. 32,991. Term of patent 14 years.

To all whom it may concern:

Be it known that I, SPENCER U. BOEHMER, a citizen of the United States, residing at Lombard, in the county of Du Page and State of Illinois, have invented a new, original, and ornamental Design for a Bottle, of which the following is a specification, reference being had to the accompanying drawing, forming a part thereof.

The drawing is a front elevation of a bottle, showing my new design. The body of the bottle is clear rough glass, and the cap and base are black. The opposite side of the bottle is the same in appearance as the side shown.

I claim:

The ornamental design for a bottle as shown and described.

SPENCER U. BOEHMER.
